[57] CLAIM

The ornamental design for a toilet, as shown and described.

DESCRIPTION

FIG. 1 is a perspective view taken from the top, front and left side of a toilet showing our new design;

FIG. 2 is a top plan view thereof;

FIG. 3 is a front elevational view thereof;

FIG. 4 is a bottom plan view thereof;

FIG. 5 is a left side elevational view thereof, the right side being a mirror image of the left side shown;

FIG. 6 is a cross-sectional view taken on line 6—6 of FIG. 2; and

FIG. 7 is a cross-sectional view taken on line 7—7 of FIG. 2.

The broken line representations of holes in FIGS. 1-4, 6 and 7 are for the purpose of illustration only.
